UNITED STATES PATENT OFFICE.

JAMES G. PATE, OF DILLSBORO, INDIANA.

AIR MOISTENER.

Application filed August 7, 1922. Serial No. 580,383.

To all whom it may concern:

Be it known that I, JAMES G. PATE, a resident of Dillsboro, in the county of Dearborn and State of Indiana, a citizen of the United States, have invented certain new and useful Improvements in Air Moisteners, of which the following is a specification.

This invention is an attachment for internal combustion engines by the use of which moisture will be supplied to the fuel charge in order that the vaporization of the charge will be more complete than heretofore and the deposit of carbon will to a great extent be overcome with the result that the engine may be more economically and efficiently operated. The invention is illustrated in the accompanying drawings and will be hereinafter fully described, the novel features being particularly pointed out in the appended claims.

In the drawings, Figure 1 is an elevation of the manifolds of an engine and the carbureter showing my improved humidifying device in connection therewith.

Figure 2 is an enlarged vertical section on the line 2—2 of Figure 1, and

Figure 3 is a section on the line 3—3 of Figure 2.

The intake manifold 1, the exhaust manifold 2, and the carbureter 3 may be of any approved or well-known form. In carrying out my invention, I employ a bowl-like casing 4 forming a water chamber in the top of which is fitted a cover 5 having a central depending nozzle 6 fitted in a central opening in the bottom of the bowl, suitable packing 7 being provided to prevent leakage. A drain cock 8 is also provided in the bottom of the bowl in order to facilitate cleaning or repairing when necessary. Across the cover 5 extends an air pipe or tube 9, interrupted interiorly by a diaphragm or baffle 10 extending across the upper portion of its inlet passage 11. At the inner side of the baffle 10, the air tube is constructed with an internal annular shoulder 12 upon which rests the edge of a mixing ring 13, the outlet passage 14 leading from a point directly above said ring as clearly shown. A pipe or tube 15 connects the outlet passage 14 with the air inlet port of the carbureter. Around the bowl 4 is placed a band or strap 16, the ends of which are secured to the clamping brackets 17 which hold the intake manifold to the engine block, the device being thus secured in such position that it will be kept

at a high temperature by the heat radiated from the exhaust manifold.

Alined axially with the mixing ring 13, a mixing tube 18 is secured in the nozzle 6 in concentric spaced relation to the nozzle. This mixing tube has an annularly enlarged head 19 seating closely in the upper end of the nozzle and having an inlet jet opening 20 formed through its side at an angle to its radius, the top of the head being closed except for a central opening 21 which forms a seat for a needle valve 22. The said needle valve is threaded through a cap 23 on the top of the air tube 9 and controls the flow of steam or vapor through the opening or port 21. Through the lower portions of the nozzle 6 and the tube 18 are ports 24 and 25 which establish communication between the water chamber and the tube, and through the side of the nozzle at the upper end thereof is an air jet passage 26 leading directly into the jet passage 20. Air to supply the jet 26 is admitted through a small inlet port 27 extending through the edge of the cover 5 and opening into the water chamber.

A tank or reservoir 28 for a water supply is mounted on any convenient support, as for instance, the dash of a motor vehicle, and a pipe or conduit 29 leads from the tank into a receiving chamber 30 formed on the rear side of the air tube 9. A port 31 in the bottom of the chamber 30 leads into a valve chamber 32 formed in the rear wall of the tube 9 immediately below the chamber 30. A plunger valve 33 is provided in the valve chamber 32 and projects through the bottom of the valve chamber to rest upon a lifter 34 extending from a rock shaft 35 mounted in the upper portion of the water chamber and controlled by a float 36 so that the water in the bowl will be maintained at a constant level in an obvious manner.

When the engine is running, fuel is drawn by suction through the carbureter and the intake manifold to the engine cylinders and the hot spent gases pass out through the exhaust manifold which quickly acquires a high temperature and radiates heat which plays directly upon the bowl or water chamber 4 and the parts carried thereby. The bowl and the water therein are thus raised in temperature so that the water is converted into steam or vapor. The suction through the carbureter creates a suction through the air tube 9, drawing hot air into and through the same and the pipe 15 to the carbureter.

A small jet of air is also drawn in through the passage 27 to flow through the openings 26 and 20, the approximately tangential disposition of the opening 20 causing the jet of air to whirl within the head 19 of the mixing tube. It will be noted that the lower end of the mixing ring 13 is below the lower wall of the inlet passage 11 and close to the head 19, the ring being spaced from the surrounding wall except where its outward overhanging upper edge rests upon the shoulder 12. Consequently, the large inflowing current of hot air is caused to turn downward around the mixing ring and pass under the lower end thereof before rising through it. A strong suction through the ring is thus set up and steam or vapor is drawn through the port 21 to pass through the ring and commingle with the air, passing with the same through the pipe 15 to the carbureter where it is mixed with the fuel flowing to the intake manifold. The combustion chambers of the engine are consequently supplied with a hot moist explosive mixture, materially aiding combustion and economizing in the amount of fuel oil required to obtain the maximum efficiency of the engine. By the use of my attachment, the deposit of carbon is minimized, inasmuch as the carbon particles are moistened and, therefore, are prevented from clinging to the surfaces of the valves, valve chambers, cylinders or others parts of the engine but are carried off with the exhaust from the engine. It will be noted that my device is exceedingly simple in the construction and arrangement and is not apt to get out of order. It is entirely automatic in operation and will require no attention from the user except to occasionally replenish the supply of water in the tank 28. The needle valve 22 may be readily adjusted so as to regulate the quantity of vapor supplied to the engine according to atmospheric conditions, the quality of the fuel, or other controlling circumstances. Should it be necessary to obtain access to the bowl or water chamber for any reason, removal of the nut on the lower end of the nozzle 6 will permit the bowl to be slipped downwardly from the nozzle, the float and the valve 33, of course, being withdrawn with the bowl. Should it be necessary, for any reason, to obtain access to the mixing chamber, it is necessary merely to remove the cap 23 whereupon the mixing ring and the mixing tube may be easily withdrawn through the top of the air tube 9. It will be particularly noted that the air jet entering the head of the mixing tube sets up a whirling action in the rising watery vapor so that an initial aeration of the vapor is effectually accomplished. The aerated vapor is taken up by the air passing over the head of the mixing tube and into the lower end of the mixing

ring where the aeration of the vapor is increased. As this larger current of air is drawn into the air tube alongside the exhaust manifold, it will have a high temperature and, consequently, will vaporize any unvaporized globules of water it may encounter and will impart to the vapor a degree of heat which will resist the tendency to condensation.

Having thus described my invention, what I claim as new and desire to secure by United States Letters Patent is:—

1. In a device for supplying water vapor to a carbureter, the combination of a water chamber, a mixing tube in communication with the water chamber, a mixing ring in axial alignment with the mixing tube, a pipe leading from said ring to the air inlet of a carbureter, and means for admitting a current of hot air between the mixing tube and mixing ring and into the mixing ring.

2. In a device for the purpose set forth, the combination of a water chamber, a mixing tube in communication therewith, means for supplying a jet of air to the tube along a chord of the same, a mixing ring in axial alignment with the tube and spaced therefrom, and means for directing a stream of hot air through the space between the tube and the ring and into and through the ring.

3. In a device for the purpose set forth, the combination of a water chamber, float-controlled means for admitting water thereto, a mixing tube within the chamber and in communication therewith, means for supplying a jet of air to the mixing tube, a mixing ring disposed above and in axial alignment with the tube, the water chamber being closed to the ring, and means for directing a current of hot air into the ring across the end of the tube.

4. In a device for the purpose set forth, the combination of a water chamber, a cover therefor, an air tube extending across the cover, a water inlet on the cover, a valve controlling the water inlet, a float within the water chamber controlling said valve, and means within the air tube whereby a current of air flowing therethrough will draw vapor from the water chamber and aerate the same.

5. In a device for the purpose set forth, the combination of a water chamber, a mixing tube in communication with said chamber, a mixing ring in axial alignment with the mixing tube, means for directing a current of hot air across the end of the mixing tube into and through the mixing ring, and means for regulating the flow from the mixing tube.

6. In a device for the purpose set forth, the combination of a water chamber, a cover therefor, an air tube extending across the cover and having a mixing chamber, a mixing ring supported at its upper

end upon the wall of said chamber and disposed below its upper end in spaced concentric relation to the chamber, a baffle across the inlet end of the air tube where-
5 by air admitted to the tube will be directed around the ring and into the lower end thereof, and a mixing tube carried by the lower end of the mixing chamber and establishing communication between the
10 same and the water chamber.

7. In a device for the purpose set forth, the combination of a water chamber, a cover therefor, an air tube extending across the cover, a mixing chamber within said tube, 15 a mixing ring supported on the wall of said chamber with its portion below its upper end in spaced concentric relation to said wall, the chamber having an outlet in one side above the mixing ring and an inlet in 20 its opposite side below the upper end of the mixing ring, a mixing tube carried by the lower end of the mixing chamber in axial alinement with the mixing ring and establishing communication between the same
25 and the water chamber, and means for admitting a jet of air to the mixing tube.

8. In a device for the purpose set forth, the combination of a water chamber, a cover therefor, a nozzle depending from

said cover and secured in the bottom of the 30 water chamber, an air tube extending across the cover and containing a mixing chamber directly over said nozzle, a cap closing the top of the mixing chamber, a mixing ring within the mixing chamber having its 35 opposite ends open to the inlet and outlet respectively of the same, and a mixing tube supported within the nozzle, the nozzle and said tube being in communication with the water chamber and the mixing tube and mixing ring being removable through the top of the mixing chamber.

9. The combination with the intake and exhaust manifolds of an internal combustion engine, and a carbureter, of a water 45 bowl, means for securing said bowl adjacent the manifold, an air tube extending across the bowl with its inlet end immediately adjacent the exhaust manifold, a pipe connecting the outlet end of said tube with the 50 air inlet of the carbureter, and means within the bowl and the air tube whereby vapor will be drawn from the bowl and aerated for delivery to the carbureter.

In testimony whereof I hereunto affix my 55 signature.

JAMES G. PATE.
